UNITED STATES PATENT OFFICE

NOEL DEISCH, OF WASHINGTON, DISTRICT OF COLUMBIA, ASSIGNOR TO LOCKE INSULATOR CORPORATION, OF BALTIMORE, MARYLAND, A CORPORATION OF MARYLAND

CONDUCTOR-RELEASING CLAMP

Application filed November 11, 1929. Serial No. 406,422.

The invention relates to clamps for the suspension of the conductors forming part of high tension transmission lines.

The principal object of the invention, generally stated, is to provide a clamp adapted for suspending a conductor from the usual towers or other equivalent supports and characterized by capability of releasing its gripping action upon the conductor in the event of breaking thereof or excessive strain thereupon at one side of a tower, the result being that the conductor may slip with respect to one or more of the clamps and the strain be distributed instead of it all coming upon a single tower with possible damage thereto.

It is well known that under certain climatic conditions there may be a thick and very heavy accumulation of sleet or ice upon a transmission line and where the spans are very long it is possible that this great weight may cause breakage of the conductor or at least such tremendous sagging as to exert an excessive strain upon the adjacent tower. The same condition may occur as the result of high wind at one side or the other of a ridge and, indeed, from other causes. It is with these facts in view that I have devised the present invention which has for an important object the provision of a suspension clamp which is adapted and intended to be hung from a string of insulators, as is customary, and which will under ordinary circumstances grip the conductor with absolute firmness but which will under some circumstances release its holding action and permit the conductor to slip through.

Another important object is to provide a clamp of this character which may be described as trigger operated, that is to say one in which the holding action will be maintained until the clamp and the string of insulators suspending the same have been pulled by strain on the conductor into or beyond a certain predetermined inclination whereupon release occurs, not gradually, but suddenly and completely so that there will be a quick release.

Another object of the invention is to provide a clamp of this character which after release will not automatically reassume its

clamping action with possible detriment to an unarmored portion of the conductor in cases where armor is provided where the clamps are located, but which will remain open until manually reset in a proper manner by a repair tool.

Another object is to provide a clamp in which a certain freedom of movement or swinging of the clamp itself and supporting insulators may take place, as for example during ordinary windy weather conditions, or expansion and contraction of the conductor in a span affected by local temperature variations without releasing it, it being necessary that the inclination exceed a certain safe limit before release occurs.

A further object is to provide a clamp of this type in which the parts cannot become disassociated and lost when release takes place, adequate means being provided for always holding the parts together under every condition.

A still further object is to provide a clamp of the character described in which there is no wear upon any of the operating faces under normal conditions, there being consequently no diminution of the clamping action resulting from prolonged use.

An additional object is to provide a clamp of this type which will be simple and inexpensive to make, easy to apply or use, positive in action, efficient and durable in service, and a general improvement in the art.

To the attainment of the foregoing and other objects and advantages, the invention preferably consists in the details of construction and the arrangement and combination of parts to be hereinafter more fully described and claimed, and illustrated in the accompanying drawings in which:

Figure 1 is a side elevation of a clamp constructed in accordance with my invention and showing it in operative or clamping position,

Figure 2 is a similar view showing the parts in released position,

Figure 3 is a top plan view,

Figure 4 is a bottom plan view,

Figure 5 is an end elevation, and

Figure 6 is a fragmentary view partly in

elevation and partly in section showing a slight modification.

Referring more particularly to the drawings I have shown the device as comprising a lower clamping member 10 formed as an elongated body with the seat 11 therein formed as a groove or channel. Obviously this seat may be straight throughout or curved upwardly as shown, this detail being rather immaterial. Formed on opposite sides of this body and projecting laterally therefrom are trunnions 12 which may have downwardly elongated heads 13, and also formed on the opposite sides of this member 15 near the upper portion thereof are spaced pairs of ribs or projections 14 for a purpose to be described. At the underside of the body and projecting downwardly therefrom in spaced relation to the center are lugs 15 which may be of bifurcated form and which are provided within the bifurcations with inclined abutment shoulders 16. Any suitable or preferred arrangement of webs 17 or the like may be provided for reinforcing 25 this structure.

The device further includes an upper clamping member 18 likewise formed as an elongated body received within the groove or channel 11 and adapted to engage the conductor 19 for clamping the same. Regardless of whether the lower clamping member has its seat longitudinally curved or of serpentine form or straight, the upper clamping member should correspond so as to obtain 35 the proper clamping action. This upper clamping member is represented as having spaced pairs of transverse ribs 20 on its top, the inner ones of which are preferably braced by a longitudinal web 21 extending 40 between them, and these ribs 20 serve as retaining means for U-bolts 22 which straddle the assembled upper and lower clamping members and which have their lower ends passing through holes 23 in yoke-like members 24 located beneath the lower clamping member and formed with abutment shoulders 25 of inclined form cooperating with the shoulders 16. The U-bolts are equipped 45 with nuts 26 threaded thereonto and operating to hold the clamping members 10 and 18 in clamping relation upon the conductor.

In addition to the shoulders 16, the yoke members may be provided with depending extensions 16^a as shown in Figure 6.

55 The suspension means is here represented as comprising a pair of similar links 27 apertured at their upper ends for passage of a suitable securing element by means of which the clamp may be suspended from the lower end of a string of insulators. At their lower ends these links are shown as having vertically elongated openings 28 rockably engaged upon the trunnions 12. The purpose in elongating the openings 28 is to permit 60 them to be slipped over the elongated heads 65

13 of the trunnions, it being clear that afterwards the lower ends of the heads 13 will overlie the outer surfaces of the links at the lower ends of the elongated openings or slots therein so that lateral separation of the 70 links with respect to the clamp will be prevented.

The means for maintaining the clamping relation of the lower and upper clamping members 10 and 18 upon the conductor includes, in addition to the U-bolts and nuts above described, a toggle mechanism including a pair of links 29 pivotally connected at 30 with the yoke-like members 24 and pivotally connected with each other, as by a transverse pin 31 which projects laterally beyond both sides as clearly indicated in Figure 4, it being preferable to provide cotter pins 32 for preventing this pin from shifting laterally out of place. Though it is not necessary the trunnions above referred to may likewise be equipped with cotter pins 33 for the same reason.

Under normal circumstances the toggle links 29 are off center upwardly as shown by dot and dash lines in Figure 1 and are held stable by bearing against a lug 29^a on the underside of the lower clamping member. Under these conditions the shoulders 25 will engage the shoulders 16, and in the modified 95 form the extensions 16^a, the result being that the yokes 24 will be maintained in their normal position serving as abutment means for the securing nuts 26 on the U-bolts, the U-bolts then operating to hold the members 10 and 18 firmly in clamping position upon the conductor.

In order to effect release of the clamping action upon the occurrence of an excessive strain upon the conductor at either side of the tower or other support where the clamp is mounted, I provide cam means for breaking the toggle defined by the links 29. In the present instance this is shown as comprising cam projections 34 at the lower portions of the links 27, these cam projections being at the ends of a curved surface 35 which normally clears the pin 31. It is preferable that both links be formed in the same manner for cooperation with both projecting ends of the pin 31.

The clamp may be installed by placing the lower clamping member against the underside of the conductor, placing the upper clamping member within the groove or channel 11, engaging the links 27 upon the trunnions 12, and then placing the U-bolts 22 between the pairs of ribs 20, after which the toggle assembly is placed in position by engaging the apertured yokes 24 upon the ends 125 of the U-bolts. The nuts 26 are then applied and screwed down while the links 27 are in normal or vertical position. The links 29 should be pushed upwardly into engagement with the lug 29^a so that the toggle will be 130

stable on account of being off center upwardly. The nuts 26 are screwed down until the conductor is gripped just as firmly as desired. After installation has been effected 5 in this manner it is apparent that there will be a strong clamping action which will be maintained until the toggle is broken. Owing to the fact that the curved surface 35 extending between the cam projections 34 is 10 out of engagement with the projecting ends of the pin 31 it is apparent that there is no wear on the parts which will eventually reduce the clamping action and permit slippage. This is of importance as it is possible 15 for the clamp and the string of supporting insulators to sway to a certain extent, as for example in windy weather, without effecting release of the clamp. However, in case there is an excessive strain upon the conductor at 20 either side of the clamp, which strain might be caused by breakage of the conductor or an accumulation of ice or sleet thereon, it will be apparent that the clamp will be moved to one side or the other, thus pulling 25 the suspension links 27 into inclined position as shown by dot and dash lines in Figure 1 and full lines in Figure 2. When this angular inclination exceeds a certain predetermined degree, one or the other of the sets 30 of cam projections 34 will engage against the projecting ends of the pins 31 and force the same downwardly, thus breaking the toggle defined by the links 29 and moving the yokes 24 toward each other so that the abut- 35 ment shoulders 25 thereon will ride off from the shoulders 16 and instantaneously release the clamping action by permitting the yokes 24 to move upwardly against the underside of the lower clamping member 10. This will 40 open the clamp to a very noticeable extent and will permit the conductor to slip through so that the unequal strains thereon may be distributed possibly throughout several spans. A feature of importance is that after 45 such an excess strain is removed the clamp will not regrip the cable and there will be consequently an absence of abrasion or mutilation of the cable such as might occur particularly if the cable be unarmored where it 50 is intended to be gripped.

From the foregoing description and a study of the drawings it will be apparent that I have thus provided a very simply constructed, easily applied and positively operating clamp which will maintain the desirable clamping action under all normal conditions but which will automatically release its gripping action when such is desired to take care of the distribution of excessive strains which might otherwise cause damage to towers or other supporting structures from which the conductor is suspended. It is believed that the construction, operation and 65 advantages should be readily apparent to one

skilled in the art without further explanation.

While I have shown and described the preferred embodiment of the invention, it should be understood that the disclosure is 70 merely an exemplification of the principles involved as the right is reserved to make all such changes in the details of construction as will widen the field of utility and increase the adaptability of the device provided such changes constitute no departure from the spirit of the invention or the scope of the claims hereunto appended.

Having thus described the invention, I 80 claim:

1. In a releasing clamp, lower and upper clamping members disposable against a conductor, suspension means for the assembled conductors, toggle means for holding said clamping members in clamping relation upon the conductor, and means operable upon relative swinging movement of the suspension means beyond a predetermined extent for releasing the toggle means.

2. In a releasing clamp, lower and upper clamping members disposable against a conductor, suspension means for the assembled conductors, toggle means for holding said clamping members in clamping relation upon the conductor, and means operable upon relative swinging movement of the suspension means beyond a predetermined extent for releasing the toggle means, comprising cam elements on the suspension means cooperating with projecting portions of the toggle 90 means.

3. A conductor releasing clamp comprising upper and lower clamping members disposable against a conductor, suspension means for the assembled clamping members movable with respect thereto, means embracing the clamping members for holding the same normally in clamping relation and including a toggle structure, and cam means on the suspension means engageable with the 100 toggle for breaking the same.

4. A conductor releasing clamp comprising upper and lower clamping members disposable against a conductor, suspension means for the assembled clamping members movable with respect thereto, U-bolts straddling the clamping members, yokes carried by the U-bolts and serving as abutment means for nuts on the U-bolts, toggle means connecting the yokes and normally holding them separated and in effective position, and means on the suspension means engageable with the toggle for breaking the same and drawing said yokes toward each other into ineffective position.

5. A conductor supporting clamp comprising a pair of clamping members disposable against a conductor, suspension means for the assembled clamping members movable with respect thereto, abutment elements on 130

- one clamping member, bolt means engaging the clamping members for normally holding them in clamping relation upon the conductor, means engaged with said bolt means and
5. cooperating with said abutment means and connected by toggle means for holding the bolt means effective, and means on the suspension means engageable with the toggle means, upon relative movement of the sus-
10. pension means beyond a predetermined extent, for breaking the toggle and rendering the bolt means ineffective.
6. A conductor supporting clamp comprising upper and lower clamping members dis-
15. posable against a conductor, abutment shoulders on the lower clamping member, suspension means for the assembled clamping members swingable with respect thereto, U-bolts engaging the clamping members, yoke mem-
20. bers beneath the lower clamping member carried by said U-bolts and normally engag-
- ing said abutment shoulders, toggle means connecting said yoke members for normally holding them in effective position, and means
25. cooperating with the toggle means and sus-
- ension means for moving and breaking the former to render said yoke means ineffective upon swinging movement of the suspension means beyond a predetermined extent.
30. 7. A conductor supporting clamp comprising a pair of clamping members disposable against a conductor, suspension means for the assembled clamping members swingable with respect thereto, means including a tog-
35. gle for maintaining said clamping members in clamping relation to the conductor, and means operable upon swinging movement of the suspension means beyond a predetermined extent for breaking the toggle.
40. 8. A conductor suspension clamp comprising a pair of clamping members disposable against a conductor and equipped with sus-
- ension means, and means including a toggle for maintaining the clamping members in
45. clamping relation to the conductor.
9. A conductor suspension clamp comprising a pair of clamping members disposable against a conductor and equipped with sus-
50. pension means, and means including a toggle for maintaining the clamping members in clamping relation to the conductor including cam means on the suspension means.

In testimony whereof I affix my signature.
NOEL DEISCH.
